UNITED STATES PATENT OFFICE.

EUGENE P. WALTERS, OF CAMAS, WASHINGTON.

DOCTOR-OPERATING MECHANISM FOR CALENDERING-MACHINES.

1,200,400.

Specification of Letters Patent.

Patented Oct. 3, 1916.

Application filed December 17, 1915. Serial No. 67,472.

To all whom it may concern:

Be it known that I, EUGENE P. WALTERS, a citizen of the United States, and a resident of Camas, Clark county, State of Washington, have invented a new and useful Improvement in Doctor-Operating Mechanism for Calendering-Machines, of which the following is a specification.

This invention relates to mechanism for 15 operating the doctors used in calendering machines.

One of the main objects of this invention is to provide suitable power-operated means, adapted to simple and flexible control, for 15 throwing the doctors into or out of operative position relative to the calender rolls.

Another object is to provide means for regulating the pressure with which said doctors bear on the calender rolls when said 20 doctors are in their operative position.

I attain these objects of my invention by connecting the doctors to a single member, to which is imparted longitudinal movement by any means, for example by connecting 25 such member to a piston head reciprocable in a cylinder connected to a source of fluid or liquid under pressure, and controlling the position of the piston in the cylinder by admitting the operating fluid or liquid into or 30 discharging same from the cylinder.

In the accompanying drawings: Figure 1 is a vertical section of a calendering machine showing my doctor-operating mechanism as used in connection therewith, the 35 doctors being in operative contact with the rolls; Fig. 2 is a sectional view of one of the pneumatic means used for positioning the doctors as desired; Fig. 3 is a vertical section on the line 3—3 of Fig. 1; Fig. 4 is a 40 fragmental view showing a different optional arrangement of my invention; and Fig. 5 is a fragmental view showing still another form in which my invention may be arranged.

45 *a* represents one of the side frame members of a calendering machine, and *b* are the rolls. The paper *c* traverses the machine in the direction indicated by the arrows in Fig. 1. The movable doctors *d* and the fixed doctor *e* are arranged on opposite 50 sides of the consecutive rolls. The doctors *d* are pivotally mounted on blocks *f*, adapted for vertical adjustment in the vertical guideways *g* which are fixed on the frame members *a*. The doctor *e* is rigidly mounted on a movable block *i*, in the corresponding

guideway *g*, but as this doctor is usually maintained in permanent position, it is not connected to the operating mechanism which forms the essence of my invention. 60

Mounted on the upper end of the machine are the pneumatic cylinders *j*, in which are reciprocable pistons *n*. See Fig. 2. Vertical members *k* are slidably supported in vertical guideways *l*, and the upper ends of 65 these members are connected to the piston rods *m* of said piston heads *n*. Powerful compression coil springs *o*, underlying the piston heads normally hold the pistons *n* and therewith the members *k* in their up 70 position. Check-valves *p* are provided in the lower end of each cylinder *j*, and a fluid admission conduit *q* connects the upper end of each cylinder with a source of fluid under pressure, such as air, steam, or water, 75 and a two-way valve *r*, located in the line of such conduit *q*, as shown in Fig. 1, provides convenient means for controlling the pressure imposed on the pistons. Slots *s* in the longitudinally movable members *k* have 80 pins *t* which connect the sides of the yoked fulcrumed arms *u* of the doctors *d*. Balance tension springs *v* connect the pins *t* with the members *k* at the opposite ends of the slots *s*, and form yielding means for insuring the 85 efficient operation of the doctors.

Normally the piston heads *n* are in their up position, the valve *r* being in position for allowing the fluid from the cylinders to exhaust into the atmosphere. The doctors will 90 then be in inoperative position, that is, away from the rolls *b*. When said doctors are to be placed into operative position against the rolls, the valve *r* is operated so as to admit fluid into the cylinders *j*. The members *k* 95 will then be moved downward and the lever action exerted will thus throw the doctors into operative position against the calender rolls. By the operation of the valve *r*, the pressure exerted on the piston heads is 100 regulated at will. It is apparent that the cylinders *j* may be open-bottomed, if so desired.

In Fig. 4 the construction shows but one cylinder *w* instead of two, as in Fig. 2. Said cylinder *w* is horizontal, and is provided with a piston *x* having opposed piston rods *y*, slideable in horizontal guideways *z* of the frame. Bell-crank 4 are pivoted on fixed studs 5; one end of each bell-crank being 110 pivoted to the upper end of one of the vertical, longitudinally movable members *k*,

and the other end being connected to the adjacent piston rod *y*. A conduit 6, carrying the fluid under pressure, is divided into the two branches 7, 8 which are connected 5 to opposite ends of the cylinder *w*. Two-way valves 9 are located in each of the two branches, and said valves are provided with operating levers 10, connected by a link 11, which causes them to move in synchronism, 10 and in opposite directions. A sprocket 12, fixed on the spindle of one of the valves 9, carries a drive connection 13 which runs over a hand wheel 14, located at a convenient point in reach of the operator. By 15 this arrangement of valve control, when fluid is admitted in one side of the cylinder, it will be exhausted from the other side, and the piston will move accordingly. When the piston moves to the right the members *k* 20 will be lowered and the doctors thus thrown into operative position, and vice versa.

In Fig. 5 the upper ends of the members *k* are provided with armatures 15 and collars 16. Expansion springs 17, underlying 25 the collars 16, normally hold the longitudinally movable members *k* in elevated position. Solenoids 18 are in circuit with the conductors 19.

20 is a control switch and 21 is a rheostat. 30 When the switch 20 is closed the armatures will be attracted downward so as to lower the members *k* and thus place the doctors in operative position, and the operation of the rheostat 21 will regulate the force of the 35 attractive pull of the solenoids.

The expression "power operated means" for causing the doctors to bear on the rolls with desired force, is used to designate the cylinder-and-piston element, or solenoid, 40 as the case may be.

I claim:

1. In a machine of the character described, including rolls and doctors adapted for bearing upon the circumference of the 45 rolls, the combination of a longitudinally movable member, means connecting the doctors to said member, and adapted to effect the bearing of the doctors on the rolls, a source of power, means actuated thereby 50 which are connected with and are adapted to effect the movement of the longitudinally movable member, and means for controlling the application of power.

2. In a machine of the character described, including rolls and doctors adapted 55 for bearing upon the circumference of the rolls, the combination of a longitudinally movable member, means yieldingly connecting the doctors to said member, and adapted to effect the bearing of the doctors on 60 the rolls, a source of power, means actuated thereby which are connected with and are adapted to effect the movement of the longitudinally movable member, and means for controlling the application of power. 65

3. In a calendering machine including a plurality of rolls and doctors adapted to bear upon the latter, the combination of fulcrumed arms supporting said doctors, a longitudinally movable member, connections between said longitudinally movable member and said arms, a fluid operated cylinder-and-piston element, the piston of which is connected to the longitudinally 70 movable member, and means for controlling 75 the admission and emission of the operating fluid into and out of said cylinder.

4. In a calendering machine including a plurality of rolls and doctors adapted to bear upon the latter, the combination of 80 fulcrumed arms supporting said doctors, a longitudinally movable member, yielding connections between said longitudinally movable member and said arms, a fluid operated cylinder-and-piston element, the piston of which is connected to the longitudinally 85 movable member, and means for controlling the pressure of the operating fluid in said cylinder.

5. In a calendering machine including a 90 plurality of rolls and doctors adapted to bear upon the latter, the combination of fulcrumed arms supporting said doctors, a longitudinally movable member provided 95 with longitudinal slots, pins extending through the slots of said member and connecting the fulcrumed arms of the doctors with the latter, balance springs adapted to hold the pins in normal position in the slots of said member, a fluid operated cylinder-and-piston element the piston of which is 100 connected to the longitudinally movable member, and means for controlling the pressure of the operating fluid in said cylinder.

EUGENE P. WALTERS.
